UNITED STATES PATENT OFFICE

2,330,596

FILLING MACHINE

Irwin Kotcher, Brooklyn, N. Y.

Application July 23, 1943, Serial No. 495,956

5 Claims. (Cl. 226—95)

This invention relates to a container filling machine and is an improvement over that forming the subject matter of an application filed by me on May 19, 1937, Serial No. 143,583, which has matured into Patent No. 2,167,894, dated August 1, 1939.

The present invention together with its objects and advantages will be best understood from a study of the following description taken in connection with the accompanying drawings 10 wherein:

Figure 1 is an elevation of the invention.

Figure 2 is a section on the line 2—2 of Figure 1.

Figure 3 is a section on approximately the line 3—3 of Figure 1.

Figure 4 is a section on the line 4—4 of Figure 3.

Figure 5 is a section on the line 5—5 of Figure 4.

Figure 6 is a section on the line 6—6 of Figure 4.

Figure 7 is a section on the line 7—7 of Figure 1.

Figure 8 is a section on the line 8—8 of Figure 4.

Figure 9 is a section on the line 9—9 of Figure 4.

Figure 10 is a section on the line 10—10 of Figure 1.

Figure 11 is a section on the line 11—11 of Figure 1.

Figure 12 is a section on the line 12—12 of Figure 1.

Figure 13 is a section on the line 13—13 of Figure 12.

Figure 14 is an elevation with parts broken away and parts in section showing a modification of the invention.

Figure 15 is a section on the line 15—15 of Figure 14.

Figure 16 is a section on the line 16—16 of Figure 14.

Figure 17 is a section on the line 17—17 of Figure 14.

In these drawings the letter A indicates a supporting frame which is provided with the foot portions 1 to which the frame is connected by the adjusting means 2 so that the height of the frame can be adjusted from the floor or other surface. The top part of the frame at the ends thereof has the grooved rollers 3 journaled therein for the endless conveyor 4 which is composed of a plurality of endless coil springs which engage the grooves of the rollers, the springs being spaced apart as shown in Figure 2. The rear roller is driven from a motor M through means of a belt and pulleys shown generally at 5 and the front end of the conveyor is adapted to receive cartons as they come from a waxing machine. Guide rails 6 are supported by the upper part of the frame, one on each side of the conveyor.

Uprights 7 are supported at their lower ends from upper portions of the main frame and a main tank or reservoir 8 has depending brackets 9 connected with its bottom which are connected to the uprights by screws 10. This reservoir or main tank is to receive the milk or other liquid to be placed in the containers C. This reservoir 8 has a longitudinally extending row of valve devices V extending through its bottom and these devices may be of any suitable form though each device is illustrated as composed of a tube 9 having an enlarged lower end threaded in an opening in the bottom of the reservoir and said enlarged end having openings 10 therein for permitting the liquid to pass from the reservoir into the lower end of the tube and a vent tube 11 passing through the tube 9 and suitably supported therein and having the stem 12 of a vent valve 13 connected with its lower end, a spring 14 tending to hold the valve 13 against a valve seat 15 at the lower end of the inner tube 11. A sleeve 16 has a sliding fit on the lower end of the tube 9 and is normally held with its lower end engaging the exterior part of the seat 15 by a spring 17, an exterior flange 18 being formed on the lower part of the sleeve for engagement by the lid 19 of a measuring tank 20 when said tank 20 is in raised position. As will be seen from Figure 11 when the tank 20 is in raised position the valve devices V will be opened so that liquid can pass from the reservoir 8 into the measuring tank and air will be vented from the measuring tank through the inner tube 11. This measuring tank 20 is divided into a plurality of chambers, one for each valve device so that each chamber will receive liquid from the reservoir when measuring tank has been raised. In order to vary the capacity of the chambers of the measuring tank I provide interchangeable fillers 21 of different sizes which are placed in the chambers as shown in Figure 11, each filler being of tubular shape. The lid 19 of the measuring tank is removably held on the tank by the clamping devices 22, each of which is equipped with a screw 23 in its lower bent end for engaging the bottom of the tank to cause its upper bent end to engage the lid, see Figure 7.

Each chamber of the measuring tank has a tube 24 depending therefrom, the upper end of the tube being threaded in a hole in the bottom of the chamber and the tube is locked in place by a nut 25. A sleeve 26 has a sliding fit on each tube 24 and a head 27 is threaded on the lower end of each tube, and a spring 28 encircles the sleeve and has its upper end bearing against the nut 25 and its lower end against a part of

the head. Each head is formed with the depending and diverging flanges 29 on its sides. The lower end of the tube 24 is provided with openings 30, see Figure 12, and a plug 31 fits in the lower end of the tube and has its upper end formed with a sloping wall 32 for deflecting the liquid passing through the tube 24 through the openings 30 and toward the farthest corner of a container C. It is to be understood that this device is mainly designed for use with containers or cartons having an opening in its top which is placed near one corner and this deflector 32 deflects the milk to the farthest corner. It will also be understood that when the head 27 is in lowered position, due to the action of spring 28, the lower end of the sleeve will close the opening 30 and thus no liquid can escape from the lower end of the tube, Figure 12 showing the parts in raised position for permitting the liquid to pass from the tube 24 into a container or carton.

The measuring tank 20 has projections 33 at its ends formed with vertical holes through which pass the guide rods 34, see Figure 10, the rods being supported by the uprights 7 and a spring 35 is placed on each rod under the projection 33 and acts as a cushion for the measuring tank.

The measuring tank 20 is moved vertically in the following manner. A pair of bars 36 is pivoted as at 37 to a lower part of the main frame and a cross bar 38 is pivoted to the upper end of each bar 36 and a link 39 is pivoted at its lower end to an intermediate part of each cross bar 38 and at its upper end to a bracket 40 depending from the bottom of the measuring tank. A short bar 41 is pivoted to the other end of each bar 38 and has its lower end threaded to a link or bar 42, this bar having its lower end threaded to a short bar 43 which is pivoted to one end of a bar 44 which has its other end pivoted to a lower part of each bar 36. Each bar 44 carries a hanger 45 which carries a roller 46 and these rollers engage the cams 47 on a horizontally arranged shaft 48 journaled in the lower part of the main frame and driven from a motor M' by the gearing 49. It will be understood that by threading the link 42 to the parts 41 and 43 the amount of movement imparted to the tank 20 by the cams 47 can be adjusted. Of course, these cams 47 are so formed as to hold the measuring tank in raised position a sufficient length of time to permit the chambers of said tank to be filled from the reservoir and as will be seen from Figure 11 when the tank 20 is raised it will open the valve means V so that milk or liquid will flow from the reservoir into the chambers of the tank 20. Then when the proper amount of liquid has been placed in the chambers of the tank 20 the rollers 46 are engaged by the low parts of the cams 47 so that the measuring tank moves downwardly and the valve means V closed.

The elevator E for elevating the cartons from the conveyor against the heads 27 of the valve means depending from the tank 20, is composed of a plurality of elongated plates 50 set on edge and the spacer members 51 placed between the lower parts of the plates so that the plates are spaced apart and are arranged to pass between the springs of the conveyor 4 as shown in Figure 7. The plates 50 of the elevator pass through slots in an inverted horizontally arranged channel member 52, forming a part of the main frame and over which the upper reach of the conveyor 4 passes. The bottom of the elevator is con-

nected with the upper ends of the rods 53, the rods being arranged in pairs, as shown in Figure 3, and the lower ends of the rods of each pair are connected together by a cross piece 54, see Figure 4, and said rods pass through cross pieces 55 at the lower part of the frame and also through bushings 56 formed in a drip pan 57 suspended under the upper portion of the main frame by the hangers 58 as shown more particularly in Figures 1, 7 and 10, this pan, of course, receiving any liquid dripping from the parts of the apparatus. Thus the rods 53 are guided for vertical movement and as shown in Figure 3 they are preferably of rectangular shape in cross section and the openings through which they pass are of the same shape. As shown more particularly in Figure 4 a pair of levers 59 are pivoted intermediate their ends to the lower part of the main frame as shown at 60 and the outer ends of these levers engage under the cross pieces 54. A short yoke 61 is pivoted at one end to a part of the main frame and its other end rests on the inner ends of the levers 59, as shown in Figures 4 and 8 and said other end of the yoke carries a roller 62 for engagement by a cam 63 on the shaft 48. Thus when the yoke 61 is depressed by the cam 63 the levers 59 are tilted so that the outer ends will raise the rods 53 which results in raising of the elevator to lift a group of cartons C off the conveyor and to cause the upper ends of the cartons to engage the heads 27 of the valve means depending from the tank 20 which opens such means to permit liquid from the tank 20 to enter the cartons as shown in Figure 12. As will be seen from this figure as the carton is raised the conical end of the plug 31 enters the opening in the carton and then the head 27 is pressed upwardly to cause the sleeve 26 to move above the openings 30 so that liquid will flow from the tank 20 through the tube 24 and openings 30 into the carton.

In order to prevent the first carton of a group of cartons from being moved by the conveyor beyond filling position I provide a pair of vertically arranged shafts 64 supported for rotary movement in the frame and arranged one at one side of the conveyor and one at the opposite side thereof and these shafts are arranged adjacent the rear end of the elevator. The upper end of each shaft carries a finger 65, these fingers acting as stops for the first carton of a group when moved at right angles to the conveyor to engage said carton. Arms 66 are connected to the lower ends of the shafts and links 67 connect the arms with a slide 68 horizontally arranged in the lower part of the main frame and supported by the cross pieces 69 forming part of the main frame. The slide carries a roller 70, see Figures 2, 4 5 and 6 and a spring 71 connected with the slide holds the slide with the roller against a cam 72 on the shaft 48. This cam 72 is so formed as to cause the slide 68 to move the shafts 64 to swing the fingers 65 into holding position just before the cam 63 operates the means for raising the elevator and then to move the fingers 65 into the position shown in Figure 2 just before the cartons are placed on the conveyor by the lowering of the elevator.

I also provide a pair of shafts 73 having fingers 74 at their upper ends for stopping a carton following the group which has been moved by the conveyor over the elevator. These shafts 73 are provided with arms 75 at their lower ends which are connected by links 76 with a slide 78 provided

with a roller 79 for engagement by cam 80 on shaft 48 and a spring 81 holds the roller in engagement with the cams, these parts being similar to the parts for moving the shafts 64 and this cam 80 acts to move the shafts 13 to place the fingers 74 into holding position, as shown in Figure 2, when a group of cartons has been placed over the elevator so as to stop the following cartons from being moved by the conveyor and then when the filled cartons have been lowered upon the conveyor the fingers 74 move into inoperative position to permit another group of cartons to be placed over the elevator.

The roller 62 of yoke 61 is held in engagement with cam 63 by springs 82 connecting projections on the rods 53 with the cross pieces 55, these springs of course tending to hold the elevator and the rods 53 in lowered position and with the inner ends of the levers 59 pressing upwardly the yoke 61 to hold the roller 62 in engagement with the cam 63. A cross piece 83 connects the two bars 36 together and the pan 57 is formed with the recesses 57' in one side thereof for the passage of the members 42.

As will be seen the conveyor 4 is constantly driven from the motor M and shaft 48 is driven by motor M' and the cams on shaft 48 are so constructed and arranged that the cam 47 will raise the tank 20 to engage the valve devices V of the reservoir so that the chambers of tank 20 will be filled from the reservoir and then the tank 20 will be lowered so that the valve means will close. The conveyor will move a group of cartons over the elevator and the fingers 65 will be swung inwardly to engage and hold the first carton of the group under the last valve means of tank 20. When the last carton of the group has been placed over the elevator the fingers 74 will swing into position shown in Figure 2 to stop movement of the following cartons and then cam 63 will operate the actuating means associated therewith to raise the elevator so that the group of cartons thereon will engage the valve means of the tank 20 so that the liquid in the chambers of said tank will flow into the cartons. Then the elevator will be lowered to place the filled cartons upon the conveyor, fingers 65 will move into inoperative position so that the filled cartons can move with the conveyor from over the elevator and the fingers 74 will move into inoperative position to permit a new group of cartons to move over the elevator. The conveyor can move the filled cartons to a capping machine as in the before mentioned application.

In the modification shown in Figures 14, 15, 16 and 17 the chambered tank is eliminated and the valve means shown generally at 85 of this chambered tank are carried by the reservoir 8'. However, the tube 24' of each of these valve means 85 extends upwardly into the reservoir and a receptacle 86 has its reduced lower end slidably arranged on each of these tubes 24', these receptacles 86 taking the place of the chambers of the tank 20. A vertically movable horizontal frame 87 is located in the reservoir and the receptacles 86 pass through this frame and are removably held therein by the latch means 88 as shown in Figure 15. A pair of bars 89 are arranged at each end of the reservoir and are suitably supported for vertical movement and their upper ends are of hook construction and enter the reservoir where they are attached to the ends of the frame as shown at 90. These rods 89 are normally held in lowered position by springs 91

and they carry the rollers 92 for engaging the cams 93 on the shaft 48'. These cams 93 are so constructed and arranged that the frame 87 will be lowered before the elevator is raised so that the upper ends of the receptacles will be filled and then the frame with the receptacles 86 is raised to place the upper ends of the receptacles above the liquid level, as shown in Figure 14. Then the elevator is raised to cause the cartons to engage the valve means 85 so that the liquid in the receptacles 86 will flow through the tubes 24' into the cartons. In other respects this form of the invention is similar to that first described.

Figures 14 and 15 show a float 94 for controlling a valve 95 in an inlet pipe 96 so as to hold the liquid level in the reservoir constant and similar means may be used with the reservoir 8 in the first form of the invention.

It is thought from the foregoing description that the advantages and novel features of the invention will be readily apparent.

It is to be understood that changes may be made in the construction and in the combination and arrangement of the several parts provided that such changes fall within the scope of the appended claims.

Having described the invention, what is claimed as new is:

1. A receptacle filling machine comprising a frame, a reservoir supported at the top of the frame, vertically movable measuring chambers, a rotary shaft journaled in the frame, means actuated by the shaft for moving the chambers to a position where they will be filled with liquid from the reservoir and then move the chambers to a non-filling position, valve means depending from the chambers, a vertically movable elevator supported by the frame, a conveyor for moving receptacles over the elevator, vertically movable uprights connected at their upper ends to the elevator, levers extending in opposite directions and having their outer ends engaging lower end parts of the uprights, a roller carrying member engaging the inner ends of the levers, a cam on the shaft engaging the roller of said member for actuating the levers to cause the uprights to move the elevator vertically, said elevator when raised moving receptacles from the conveyor upwardly against the valve means for opening said valve means to permit liquid to flow from the chambers into the receptacles.

2. In a receptacle filling machine, a supporting frame, a reservoir at the top of the frame, vertically movable measuring chambers, a shaft, means actuated thereby for moving the chambers to a position where they will be filled from the reservoir and then to a non-filling position, valve means depending from the chambers, an elevator, a conveyor for conveying receptacles over the elevator, means actuated by the shaft for moving the elevator vertically, said elevator when raised moving receptacles from the conveyor against the valve means to open such valve means to permit liquid from the chambers to flow into the receptacles and when in lowered position the elevator returning the filled receptacles to the conveyor, a vertically arranged shaft adjacent the front end of the elevator, a finger on the shaft which when in one position engages a carton on the conveyor for holding the carton against movement, a second vertically arranged shaft arranged adjacent the rear end of the conveyor, a finger on the upper end of the shaft for preventing a receptacle from being moved by the conveyor from over the rear end of the

elevator, when the finger is in a certain position, a pair of slides, means for connecting the lower end of one shaft to one slide, means for connecting the lower end of the other vertical shaft to the other slide, rollers carried by the slides, a pair of cams carried by the first-mentioned shaft and engaging the rollers for actuating the vertical shafts to swing the fingers thereof into operative and inoperative position and means for holding each slide with its roller in engagement with its cam.

3. In a carton filling machine, a supporting frame, a reservoir at the upper end of the frame, a chambered member supported for vertical movement in the frame under the reservoir, valve means depending from the reservoir and opened when engaged by the chambered member when the said member is moved upwardly to permit liquid to flow from the reservoir into the chambers of said member, valve means depending from the chambers, a cross bar, a link connecting an intermediate part of the cross bar with the bottom part of the chambered member, a vertically arranged bar pivotally connected to one end of the cross bar and having its lower end pivotally connected with the frame, a second vertically arranged bar adjustable as to its length and connected at its upper end with the other end of the cross bar, a second cross bar having one end pivotally connected with the first-mentioned vertical bar and its other end pivotally connected with the lower end of the second vertical bar, a roller carried by the second cross bar, a drive shaft, a cam thereon for engaging the roller for raising and lowering the chambered member and means for forcing receptacles against the valve means of the chambered member to open the same to permit liquid to pass from the chambers into the receptacles.

4. A carton filling machine comprising a frame, a drive shaft horizontally arranged and journaled in the lower part of the frame, a reservoir supported at the top of the frame, vertically movable measuring chambers, means including cam means on the shaft for moving the chambers to a position where they will be filled from the reservoir and then moved to non-filling posi-

tion, valve means controlling the discharge of liquid from the chambers, a horizontally arranged conveyor, an elevator for raising cartons from the conveyor against the valve means for permitting liquid to pass from the chambers into the cartons, means including cam means on the shaft for moving the elevator vertically, a vertically arranged shaft adjacent the front end of the elevator, a vertically arranged shaft arranged adjacent the rear end of the elevator, a transverse finger on the upper end of each shaft, said fingers when in one position preventing movement of a carton by the conveyor and in another position permitting the carton to be moved by the conveyor, means including cam means on the shaft for operating the vertical shafts to move the fingers to operative and inoperative position and a pan located below portions of the conveyor and below the elevator for catching liquid dripping from the parts.

5. A carton filling machine comprising a frame, a drive shaft horizontally arranged and journaled in the lower part of the frame, a reservoir supported at the top of the frame, vertically movable measuring chambers, means including cam means on the shaft for moving the chambers to a position where they will be filled from the reservoir and then moved to non-filling position, valve means controlling the discharge of liquid from the chambers, a horizontally arranged conveyor, an elevator for raising cartons from the conveyor against the valve means for permitting liquid to pass from the chambers into the cartons, means including cam means on the shaft for moving the elevator vertically, a vertically arranged shaft adjacent the front end of the elevator, a vertically arranged shaft arranged adjacent the rear end of the elevator, a transverse finger on the upper end of each shaft, said fingers when in one position preventing movement of a carton by the conveyor and in another position permitting the carton to be moved by the conveyor, and means including cam means on the shaft for operating the vertical shafts to move the fingers to operative and inoperative position.

IRWIN KOTCHER.
